COIN CONTROLLED MECHANISM

Burns S. Watling, Chicago, Ill., assignor to
 Watling Scale Company, Chicago, Ill., a corpora-
 tion of Illinois

Application March 25, 1938, Serial No. 198,020

9 Claims. (Cl. 194—55)

The invention relates to coin controlled mechanisms such as are commonly employed on weighing scales, fortune-telling or other amusement apparatus, and vending machines generally, and one object of the invention is to provide an improved and fool-proof coin controlled mechanism for releasing a detent lever or like locking member of the apparatus with which the mechanism is associated and that will be reliable and efficient in operation; and another object is to provide an improved coin controlled mechanism that cannot become jammed through the introduction of one or more subsequent coins before the first deposited coin has been disposed of. 5
 Still other objects and attendant advantages of the invention will be apparent to persons skilled in the art from the following detailed description, taken in connection with the accompanying drawings in which I have illustrated one practical and preferred embodiment of the invention, and wherein—

Fig. 1 is a perspective elevation of a combined weighing scale and fortune-telling machine of the general type disclosed in the Letters Patent 25 to Thomas W. B. Watling, No. 1,923,287, granted August 22, 1933, to which my present improvements are applied.

Fig. 2 is a fragmentary enlarged front elevation showing the counter and a manually oper- 30 able plunger for operating the device.

Fig. 3 is a vertical section through the counter and one of the coin throw-outs on the line 3—3 of Fig. 1.

Fig. 4 is a rear elevation of the upper portion 35 of the machine showing a portion of the normally locked weight actuated mechanism, including a ratchet wheel and a lock and release lever cooperating therewith, with which lever my present improvements cooperate to effect the 40 release upon the deposit of a proper coin.

Fig. 5 is a side elevation of the principal parts of my improved coin controlled device, viewed on the line 5—5 of Fig. 4.

Fig. 6 is an elevation of the parts shown in 45 Fig. 5, viewed from the left of the latter figure.

Fig. 7 is a side elevation of the parts shown in Figs. 5 and 6, viewed from the side opposite that of Fig. 5.

Fig. 8 is a perspective view of a fixed guiding 50 and supporting member for most of the movable parts.

Figs. 9, 10 and 11 are progressive views in vertical longitudinal section through the coin chute and the guiding and supporting member, illustrating the positions of the movable parts as a

deposited coin moves from the position in which it first comes to rest to its point of discharge.

Figs. 12, 13 and 14 are vertical transverse sections taken on the lines 12—12, 13—13, and 14—14, of Figs. 9, 10, and 11 respectively.

Fig. 15 is a perspective view of the coin moving plunger.

Fig. 16 is a group perspective view of a coin actuated cam lever and a bell crank lever pivotally suspended thereon, which bell crank lever actuates the lock and release lever of the weight actuated member to permit the machine to function on the deposit of a proper coin.

Fig. 17 is a sectional detail on the line 17—17 of Fig. 3, showing the locking and releasing de- 15 vice of the plug which normally conceals the dial of the counter.

Referring first to Figs. 1, 2 and 4, 20 designates the base, 21 the upright casing, 21' a cap or cover, and 22 the platform of a combined weigh- 20 ing scale and amusement device of the type disclosed in the aforesaid Letters Patent to Wat- 25 ling. In the right-hand side of the cap 21' is mounted a vertical coin chute designated as an 25 entirety by 23. The upper portion of this chute is preferably flared, as shown in Figs. 5 and 7, and one edge of the chute below the flared top is open, for coin throw-out purposes as illustrated in Fig. 7. One side wall 24 of the chute is hinged at its upper end on a pivot pin 25 mounted in a 30 pair of brackets 26 secured to the opposite edge walls of the chute so that it can be opened, as shown by dotted lines in Fig. 5, to remove tooth picks, buttons, wads of paper, and other trash by which mischievously inclined persons often at- 35 tempt to beat the machine. A spring 27 normally holds the pivoted side wall 24 in closed position.

Attached to the inner side of the front wall of the cap 21' is a one-piece sheet metal guiding and supporting member designated as an en- 40 tirely by 28 and shown in isolated detail in Fig. 8. On the outer end of this member are formed lateral attachment lugs 29 receiving fastening screws 30, by which the member 28 is strongly 45 supported in horizontal position within the cap 21'. The lower end of the coin chute directly overlies this channel-shaped member 28 a slight distance inwardly of the attached end of the lat- 50 ter.

Slidably mounted in the member 28 is the coin shifting plunger that is shown in isolated perspective in Fig. 15. This comprises a block 31, the outer sides of which slidably engage the vertical side walls 32 and 33 of the support 28. 55

The forward portion of the plunger block is internally recessed and undercut to form a pair of opposed coin receiving grooves 34, and extending rearwardly from the inner walls of said grooves are a pair of ridges 35, one of which is slightly higher than the other, and the top edges of the ridges slant transversely as most clearly shown in Figs. 12, 13 and 14, so that a coin deposited before the first coin has been discharged will land on top of the ridges 35 and roll out, as indicated by dotted lines in Fig. 13. The portion of the plunger block 31 between and below the ridges 35 is longitudinally cut away to form a recess 36 to accommodate the tail portion of an upper coin throw-out device and also the depending cam portion of the cam lever, later described. On the rear end of the plunger block 31 is a plunger stem 37 that extends through a hole in the wall of cap 21' and a registering hole 20 in a stem guard 38 that is attached to the outer side of the wall 21' as by the screws 30. It may here be mentioned that the guard 38 is for the purpose of preventing slamming or other violent manipulation of the plunger. Many persons using these machines seem obsessed by an impulse to abuse and wreck the machine if they can, and devices to thwart such efforts are found to be quite essential in connection with the manually manipulated parts of such machines. The guard 38 makes it impossible for a user to actuate the plunger by a blow of his fist and compels him to limit himself to the use of his thumb or one finger.

A spring 39 (Fig. 5) anchored at one end to a lug 40 on the member 28 and at its other end to stud 41 on one side of the plunger 31 projecting through a longitudinal slot 42 in the side wall 32 of the member 28 returns the plunger, when released, to its outermost position.

Describing next the upper coin throw-out device, this consists of a lever comprising a body portion 43, a head 44, and a tail 45. The body 43 is pivoted at 46 to a lug 47 on the coin chute, and the latter is formed with an inclined slot 48 (Figs. 12 and 13) through which the head 44 plays. The upper surface of the head 44 is inclined downwardly toward the open edge of the chute so that a coin striking the same rolls out and is ejected if it is inserted when a previously deposited coin is in the position shown in Figs. 9 and 12. When the plunger carrying a previously deposited coin is in the intermediate position shown in Figs. 10 and 13, the upper throw-out member is in an inoperative position, but if a second coin is then deposited it will strike the lower throw-out (ridges 35) and be ejected, as shown in Fig. 13. The upper throw-out member normally hangs in the idle or inoperative position shown by full lines in Figs. 10 and 11 and by dotted lines in Fig. 9, but it is cammed into operative position by a coin engaging the tail 45 as the coin drops into the grooves 34 of the plunger.

The bottom wall of the member 28 is formed with a longitudinal slot 49 having a beveled rear end wall 50 (Fig. 10), and a transverse slot 51 intersecting slot 49. Slot 49 is narrower than the diameter of the coin and supports the latter at two spaced points on its rim, as shown in Figs. 12 and 13; while the length of the transverse slot 51 is greater than the diameter of the coin, so that when the latter has been pushed by the plunger into register with slot 51 on completion of the in stroke of the plunger, the coin drops into an underlying receptacle, as shown in Fig. 14.

A full stroke compelling device is preferably employed in association with the plunger. This is shown in Fig. 7, and comprises a bar 52 attached to the outer side of the side wall 33 of the member 28 and formed with a row 53 of upstanding teeth over which rides the point of a gravity pawl 54 suspended from a stud 55 mounted in one side of the plunger and extending through a longitudinal slot 56 in the side wall 33. This type of full stroke compelling device is old and well known in various arts.

Turning now to a description of the mechanism by which the plunger, acting through the coin deposited therein, rocks the locking and releasing lever (which I have designated L) so as to release for operation the weight mechanism, pivoted at 57 on an upstanding lug 58 of the member 28 is what I term a cam lever designated as an entirety by 59 and shown in isolated detail in Fig. 16. This lever has an intermediate offset portion 60, continuous with the remote end of which is a longitudinal portion 61, depending from which is a cam plate 62 formed with an inclined cam surface 62'. The lower portion of the cam plate 62 normally lies in and centrally lengthwise of the plunger supporting and guiding member 28, as shown in Figs. 13 and 14, and in line with the longitudinal recess of the plunger. Pivoted at its elbow at 63 on the free end of the arm 61 of lever 59 is an elbow lever shown in isolated detail in Fig. 16, the upper normally horizontal arm 64 of which is urged downwardly by a light spring 65 (Figs. 5 and 6) anchored at its upper end to a lateral lug 66 on lever 64 and at its lower end to a pin 67 in the cam plate 62. The depending arm 68 of the elbow lever lies crosswise of the lever L, as clearly shown in Figs. 9, 10, and 11, and is formed on its lower end with a heel 69 and a toe 70, which toe normally extends into and through the slot 49.

A spring 71 (Figs. 5 and 6) anchored at its upper end to a lug 72 on the cam lever 59 and at its lower end to a stud 73 on the side wall 32 urges both the cam lever and the elbow lever to the lower position shown by full lines in Figs. 9 and 11, the downward movement being limited by contact of the offset 60 with the top edge of wall 32 as shown in Fig. 6.

As the plunger, carrying a deposited coin as shown in Fig. 9, is pushed inwardly to the position shown in Fig. 10, the top edge of the coin riding beneath the cam 62' elevates both the cam lever and the elbow lever, against the pull of spring 71, to the position shown in full lines in Fig. 10. During this rising movement the heel 69 under the pull of spring 65 wipes across one side of the lever L, as shown by dotted lines in Fig. 10, slightly raising the arm 64 of the elbow lever against the pull of spring 65. As the coin drops out of the plunger through the transverse slot 51 (Figs. 11 and 14), the spring 71 draws both levers downwardly, and during this downward movement the heel or shoulder 69 strikes the top edge of lever L depressing the same to the dotted line position shown in Fig. 11, and this releases the scale operating mechanism, and at the same time the plunger is retracted to starting position by its spring 39. During the final part of the downward movement of the two levers, the toe 70 cams over the beveled end 50 of the slot 49 and thus disengages the heel or shoulder 69 from the lever L, permitting the latter to return to locking position.

The up and down swinging movement of the cam lever 59 actuates the counter. Projecting 75

laterally of the lever arm 61 is a pin 74 that rides in a longitudinal slot 75 of a crank arm 76 (Figs. 6 and 7) that is fast on the shaft 77 of the counter so that during each complete rising and falling movement, the counter registers one unit.

Integral with the side wall 33 of the plunger support and guide 28 is a laterally extending bracket plate 78 to which is attached, as by a screw 79 and bolt 80, a counter 81. Opposite the 10 face of the counter there is a hole in the front wall of the cap 21' (Figs. 2 and 3) through which extends the barrel 82 of a lock, and encircling the inner portion of the lock barrel is a collar 83. On the rear end of the lock barrel 82 is an under- 15 cut guide groove 84 (Fig. 17) in which is slidably mounted a locking bar 85. In the locking bar 85 is a transverse slot 86 engaged by an eccentric pin 87 on the inner end of the rotatable member 88 (Fig. 17) of the lock that is turned on the insertion of a proper key. The length of the locking bar 85 is slightly less than the diameter of the barrel 82. In the normal locking position of the bar 85, shown in Fig. 17, its lower end overlaps the inner end of the collar 83, and the lock 20 25 32 cannot be withdrawn. But by inserting the key and turning the member 88 clockwise viewing Fig. 17 a half turn, the bar 85 is raised and the lock 82 can be withdrawn, exposing to view the counter tally, as shown in Fig. 2.

30 The unused coins that are returned by the upper and lower throw-out devices roll into a delivery chute shown in Figs. 3, 5 and 6. This comprises a pan formed with a downwardly and forwardly sloping bottom wall 89, vertical side 35 walls 90, and a vertical rear wall 91 that is secured to the rear side of the bracket plate 78 by the bolt 80 (Fig. 3). The forward end of the bottom wall 89 extends through a slot 92 in the front wall of cap 21' and terminates in a coin 40 holder 93. The open upper end of this return coin chute is located laterally opposite and slightly below the lower end of the open edge of the main coin chute 23. The coins that pass through the machine drop through the discharge 45 slot 51 into the upper end of an underlying chute 94 (Figs. 4 and 5) by which they are delivered to a coin box or drawer (not shown) in the base of the machine.

It may here be noted that the longitudinal slot 43 in the bottom wall of the plunger supporting and guiding member 28 is not necessary to the operativeness of the mechanism, but it is preferably employed for two reasons. In the first place, it provides an outlet directly into the chute 94 for such fraudulent tokens as tooth picks, matches, hair pins and the like, by which dishonest persons attempt to beat the machine and avoids clogging and jamming of the movable parts normally actuated by the coin in the plunger; and, in the second place, it affords a spaced two point bearing for the edge of the coin which stabilizes the latter for its thrust engagement with the cam 62'.

Although but one specific embodiment of this invention has been herein shown and described, it is to be understood that details of the construction shown may be altered without departing from the spirit and scope of the invention as defined by the following claims.

70 I claim:

1. In a coin controlled mechanism for releasing a detent element, the combination of a coin chute, a fixed plunger supporting and guiding member underlying said chute, a plunger slidable in said member and formed with means for laterally

engaging a coin dropping from said chute, a pivoted vertically movable member disposed, in its lowered position, alongside said detent element and, in its raised position, swingable to a position above said detent element, a spring urging said movable member to said position above said detent element, another spring urging said movable member to lowered position to thereby release said detent element, and means actuated by the coin on the in stroke of said plunger and from which said movable member is pivotally suspended for raising said movable member.

2. In a coin controlled mechanism for releasing a detent element, the combination of a coin chute, a fixed plunger supporting and guiding member underlying said chute, a plunger slidable in said member and formed with means for laterally engaging a coin dropping from said chute, a pivoted vertically movable member disposed crosswise of one side of said detent lever and having a shoulder, a spring acting to swing said movable member, when raised, to a position in which its shoulder overlies said detent lever, means from which said movable member is pivotally suspended and including a cam engaged and actuated by the coin on the in stroke of said plunger for raising said movable member, and another spring acting through said means to lower said movable member and thereby release said detent when said plunger is retracted.

3. In a coin controlled mechanism for releasing a detent lever, the combination of a coin chute, a fixed plunger supporting and guiding member underlying said chute, a plunger slidable in said member and formed with means for laterally engaging a coin dropping from said chute, a pivoted vertically movable member disposed crosswise of said detent lever and having a shoulder, a spring urging said movable member to lowered position, means engaged and actuated by the coin on the in stroke of said plunger for raising said movable member, and a spring urging said movable member in a direction to cause the shoulder thereon to wipe across said detent lever and snap over the top edge thereof as said movable member is raised.

4. In a coin controlled mechanism for releasing a detent lever, the combination of a coin chute, a fixed plunger supporting and guiding member underlying said chute, a plunger slidable in said member and formed with means for laterally engaging a coin dropping from said chute, a pivoted vertically movable member disposed crosswise of said detent lever and having a shoulder, a spring urging said movable member to lowered position, means including a cam engaged and actuated by the coin on the in stroke of said plunger for raising said movable member, a spring urging said movable member in a direction to cause the shoulder thereon to wipe across said detent lever and snap over the top edge thereof as said movable member is raised, and means automatically retracting said shoulder from said detent lever during the final part of the downward movement of said movable member.

5. An embodiment of claim 4 wherein the means automatically retracting the shoulder from the detent lever consists of a cam on the movable member and a cooperating surface on the plunger supporting and guiding member.

6. An embodiment of claim 2 wherein the means including a cam engaged and actuated by the coin on the in stroke of the plunger consists of a lever pivoted at one end on the plunger supporting and guiding member and the cam is

formed on said last named lever, and the movable member is pivotally suspended from the free end of said last named lever.

7. An embodiment of claim 4 wherein the 5 means including a cam engaged and actuated by the coin on the in stroke of the plunger consists of a lever pivoted at one end on the plunger supporting and guiding member and the cam is carried by said last named lever, and the movable 10 member constitutes the depending arm of a bell crank lever, the other arm of which lies alongside said cam carrying lever, and the spring urging the movable member in a direction to cause the shoulder thereon to wipe across the detent lever 15 and snap over the top edge thereof is anchored at one end to said other arm of the bell crank lever and at its other end to the cam carrying lever.

8. In a coin controlled mechanism of the class 20 described, the combination of a coin chute, a fixed plunger supporting and guiding member of rectangular cross-section underlying said chute and having in its bottom wall a longitudinal slot of less width than the diameter of the coin and a

transverse coin discharge slot intersecting said longitudinal slot, and a plunger slidable in said member, said plunger having a chamber formed with transverse grooves in its side walls registering with the lower end of said chute to receive and laterally support a coin dropping from the latter and coming to rest on the upper corners of the edges of said longitudinal slot when the plunger is in its outer position and registering with said coin discharge slot when the plunger is in its 10 inner position.

9. In a coin controlled mechanism of the class described, the combination of a coin chute having an open edge, a fixed plunger supporting and guiding member underlying said chute, a plunger 15 slidable in said member across the lower end of said chute, said plunger formed with a transverse recess to receive a coin dropping from said chute and with a top wall portion in rear of said recess inclined downwardly toward said open 20 edge and forming a throw-out for a second coin deposited after the inward movement of said plunger and first named coin.

BURNS S. WATLING.
